UNITED STATES PATENT OFFICE

ALVIN LEWIS, OF NEW YORK, N. Y., ASSIGNOR TO EMBOSOGRAF CORPORATION OF AMERICA, OF NEW YORK, N. Y., A CORPORATION OF NEW YORK

DESIGN FOR A SIGN DISPLAY STAND

Application filed August 19, 1931. Serial No. 40,890. Term of patent 14 years.

To all whom it may concern:

Be it known that I, ALVIN LEWIS, a citizen of the United States, and resident of New York city, in the county of New York and State of New York, have invented a new, original, and ornamental Design for Sign Display Stands, of which the following is a specification, reference being had to the accompanying drawings, forming a part hereof.

In the drawings, Fig. 1 is a face view of the stand showing my new design; Fig. 2 a side view of the stand; and Fig. 3 a top plan view of the stand.

I claim:

The ornamental design for a sign display stand substantially as shown.
